(57) **CLAIM**

The ornamental design for a water balloon, as shown and described.

DESCRIPTION

FIG. 1 is a front and top perspective view of a water balloon showing my new design;
FIG. 2 is a front view thereof;
FIG. 3 is a rear view thereof;
FIG. 4 is a left view thereof;
FIG. 5 is a right view thereof;
FIG. 6 is a top view thereof;
FIG. 7 is a bottom view thereof;
FIG. 8 is a rear, and bottom perspective view thereof; and,
FIG. 9 is a top perspective view thereof, showing the water balloon in an open position of use.

The broken lines illustrate portions of the water balloon that form no part of the claimed design; the dot-dash boundary lines in FIGS. 1-5 and 8-9 depict the bounds of the claimed design that form no part thereof.
